UNITED STATES PATENT OFFICE

95,056

DESIGN FOR AN INFANT'S HAND GUARD

Elizabeth S. MacLeod, Cranford, N. J.

Application January 5, 1935, Serial No. 54,735

Term of patent 3½ years

To all whom it may concern:

Be it known that I, Elizabeth S. MacLeod, a citizen of the United States, residing at Cranford, in the county of Union and State of New Jersey, have invented a new, original, and ornamental Design for Infants' Hand Guard, of which the following is a specification, reference being had to the accompanying drawing, forming part thereof, in which:—

The figure is a front view of an infant's hand guard embodying my novel design.

I claim:—

The ornamental design for an infant's hand guard, as shown.

ELIZABETH S. MACLEOD.
